BASE SHIELD AND METHOD

Charles E. Schell, Emporium, Pa., assignor to
Sylvania Electric Products, Inc., a corporation
of Massachusetts

Application July 18, 1946, Serial No. 684,608

3 Claims. (Cl. 250—27.5)

1

The present invention relates to electron tubes and to the basing of radio tubes and the like, and more particularly to the structural formation of a cylindrical metal sleeve located at the base of electron tubes, and to an improved method of forming the shield.

In tubes using a metal sleeve as a shield of the character described, the electrodes are housed within an evacuated or a gas filled glass envelope closed at one end by a header through and to which the several axially extending lead-in wires are hermetically sealed. This header end of the envelope is seated against relative rotary movement upon a wafer-like base of Bakelite or similar hard dielectric material having a plurality of axially extending tubular terminal pins within which the lead-in wires are threaded and soldered to place.

Shields of this character heretofore have comprised tubular members first drawn cup-shape from a flat stock and then made into a seamless tube by having their bottom walls punched out. This punch press method while producing a desirable shield has been costly and it is the principal object of my invention to provide an improved construction which may be fabricated much faster and far more economically.

Another object of my invention is to provide an improved construction so that even though slight variations may occur in the blank from which the shield is made a satisfactory shielded tube still results.

In the arrangements illustrated in the drawing, I provide a tubular member formed from strip metal to be used as a shield in the basing of radio tubes and the like, with a straight wall rolled long its top edge to form an inwardly turned annular flange, and having a lock seam extending but part way of its width, the opposing ends of the strip above and below the seam in abutment, the seam being pressed inwardly, all of which provides a smooth joint which throughout its entire length lies flush with the outer cylindrical surface.

The accompanying drawings illustrating the invention and forming a part of the specification are as follows:

Fig. 1 is a side view of a radio tube embodying the invention.

Fig. 2 is an enlarged fragmentary sectional detail on line 2—2 of Fig. 6.

Fig. 3 is an enlarged view of the lower end of a tube as shown in Fig. 1, part being in elevation and part in longitudinal section.

Fig. 4 is a stretchout of the blank as cut to form the shield.

2

Fig. 5 is an enlarged top plan view of the shield. Fig. 6 is a sectional view on line 6—6 of Fig. 5.

And Fig. 7 is a view, drawn to a reduced scale, showing a length of strip material and the operations performed thereon prior to its reaching horizontal sliding dies which in cooperation with a common mandrel gives it cylindrical shape and form the seam.

In the drawings similar reference numerals refer to similar parts throughout the several views.

The base with which the shield is used is a disc-like wafer 1 of Bakelite or other hard dielectric material upon which is seated the header 10 end 2 of the glass envelope 3. Electrodes within the latter are not shown as the interior construction and arrangement of the tube have no particular bearing on the invention. Lead-in wires, also not shown, are hermetically sealed in the header 2 and extend through bosses 4 on the bottom thereof, the projecting ends of the wires being threaded into and soldered to respective ones of regularly spaced, circularly arranged tubular terminal pins 5 secured to and extending axially from the base 1. In the top of the base are pockets 6 adapted to receive the bosses 4 and its peripheral edge is reduced to provide a supporting ledge 7 for the cylindrical shield 8 and an annular shoulder 9 over which the shield engages and which is locating means for centering the member 8 and holding it in concentric spaced relation to the envelope. This comparatively narrow spacing is preferably closed at its upper end by rounding the top edge of the shield into a flange 10. Before assembly a ring 11 of basing cement is mechanically applied to the inner face of the shield 8 and after assembly of the parts is hardened by a localized external application of heat to the shield, thus effectively sealing the latter to the envelope 3.

The peripheral edge of the base 1 has a plurality of regularly spaced radial notches 12 each being of a depth sufficient to form an undercut surface 13. At these points the shield is staked by a suitable kick press which forces registering portions 14 of the shield along its bottom edges inwardly to locking engage the surfaces 13 and thus hold the shield against axial displacement.

I shall now describe a method for fabricating my improved shield construction:

The shields 8 are made such as on a four-way slide machine from strip metal 15 fed from a roll along suitable guides. The feed is intermittent but at high speed and at a first station A a cutting tool operates to form opposing, open ended rectangular notches 16 while simultaneously a

second operation takes place at station B, a third operation on the top edge of the strip between stations B and C, and a fourth operation at station D.

At station B a pressure pad engaging the face of the strip produces a slight embossing 17 between opposing slots 16 which is of a greater width than that of the slots, and cutting dies function to slit the body of the strip in line with the bottoms of the slots to approximately the side edge of the embossing. That portion of a strip comprising the cylindrical wall of a shield is indicated by dimension Y, Fig. 7, the top edge of this portion of each blank when between stations B and C being engaged by a suitable tool to form the flange 10.

At station D the strip is cut transversely along a line intermediate the side edges of opposing slots 16, thus severing a blank such as illustrated at 15^a, Fig. 4, and forming the longitudinally projecting end 18 of one blank and a like part 19, but of different length, of the succeeding blank.

From station D, the strip is fed to a mandrel, not shown, in cooperation with which four angularly arranged slides movable in a horizontal plane operate to wrap the blank 15^a around the mandrel, interlock the projections 18 and 19 to form a lap seam 20 and press the latter inwardly to fill the depression of the embossed part 17. The result of this latter operation may be seen in Fig. 2 where it will be seen that the lock seam is inside the resulting sleeve thus leaving a substantially smooth outer surface.

Thus there is formed of thin strip metal a tubular sleeve for use as a shield in the basing of radio tubes and the like, such sleeve having a seam or lock joint part way of its length with its outer face flush with that of the cylindrical wall, a sleeve held to a precise diameter with opposing end edges of portions above and below the seam in abutment with each other, or substantially so depending on whether the blank is slightly over or under length, so as to completely close the tube, such sleeve having a continuous annular flange along its top edge and an unobstructed bottom edge which permits the staking at any point of its periphery to an inner engaging surface.

As hereinabove stated, in the continuous high speed feeding of strip metal on a multiple slide machine slight variations in feed may result even though stops are set for gage-like accuracy. However, by an allowance for tolerance in dimension Y, Fig. 7, and by notching the strip and slitting it, as at stations A and B, respectively, a uniform product is rapidly produced in quantity and without the wall of the shield at the ends of the seam being bulged by a crowding of its end edges or by a gap occurring by these edges being separated.

Attached to the inner surface of the shield there is shown at 21, Fig. 6, a ground wire for connection with the lead wire in one of the terminals 5.

Although I have shown and described particular embodiments of my invention, I do not desire to be limited to the embodiments described, and I intend in the appended claims to cover all modifications which do not depart from the spirit and scope of my invention.

What I claim is:

1. A base shield for plug in devices comprising

ing a one-piece cylindrical sleeve formed from a unit length of strip metal, said strip unit being united at its ends by a lock seam extending but part way between its side edges, the opposing end edges of the strip portions at the ends of said seam abutting each other, the opposing end edges of said strip being slit a slight distance inwardly at each end of said seam whereby the outer face of said seam may be made to lie flush with the outer peripheral surface of the cylindrical wall and, said sleeve having an inwardly directed flange at one end.

2. A base shield for plug in devices comprising a one-piece cylindrical sleeve formed from a unit length of strip metal with an inturned annular flange at one end of the sleeve, said strip unit being united at its ends by a lock seam extending but part way between its side edges, the opposing end edges of the strip portions at the ends of said seam abutting each other, the opposing end edges of said strip being slit a slight distance inwardly at each end of said seam whereby the outer face of said seam lies flush with the outer peripheral surface of the cylindrical wall.

3. An electron tube including a glass envelope, a base of insulating material, an annular shoulder on said base concentric with said envelope, a cylindrical sleeve supported by said base and telescoping said shoulder for centering thereby in spaced relation to said envelope, said base having a plurality of regularly spaced radially extending slots, an undercut surface at the lower end of said slots and within the periphery of said shield, an inturned annular flange on the upper edge of said shield, means for holding said shield to said base comprising segmental portions pressed from the lower edge of said shield to engage said undercut surface, said shield being formed in one piece from strip metal joined at its ends by a lock seam of a length to leave marginal portions of the cylindrical body at each end of the seam, the ends of said marginal portions abutting each other in a line intermediate the sides of said seam, and a ring of basing cement providing a glass-to-metal seal between said envelope and said shield, the outer face of said seam lying flush with the outer peripheral surface of said sleeve.
